UNITED STATES PATENT OFFICE.

WALTER CLIFF, OF WORTLEY, NEAR LEEDS, ENGLAND, ASSIGNOR TO THE
J. L. MOTT IRON WORKS, OF NEW YORK, N. Y.

BATH-TUB.

SPECIFICATION forming part of Letters Patent No. 363,048, dated May 17, 1887.

Application filed April 4, 1887. Serial No. 233,565. (No model.)

To all whom it may concern:

Be it known that I, WALTER CLIFF, of Wortley, near Leeds, in the Kingdom of Great Britain, have invented an Improvement in 5 Bath-Tubs, of which the following is a specification.

Bath-tubs have been made of fire-clay, enameled upon the inside and sometimes painted upon the outside, and a molded rim has been 10 made in one with the tub, at its upper edge. Baths of this kind are usually intended to stand without any inclosing wood-work; but in consequence of the high heat required for the hard glaze upon the surface of the tub the 15 highly-ornamental colors and glazes--such as the majolica glazes--cannot be made use of, as they are injured by the high heat.

The object of the present invention is to allow for highly ornamenting the top edge of 20 the fire-clay bath-tub, so as to better adapt it to the highly-finished bath-rooms, in which the bath-tubs are not closed around with wood-work, and at the same time allow for the use of various colors or combinations of colors in 25 the glazing or ornamenting of the surface.

In the drawings, Figure 1 is a cross-section of a bath-tub with my improved rim. Fig. 2 is a plan view of one section of the rim, and Figs. 3 and 4 are sections showing different 30 shapes of moldings applied to the top edge of the bath.

The bath-tub A is of any desired size or shape, and it is made of fire-clay or other quality of earthenware or similar material; 35 but instead of having a roll or molding at the top edge, such molding, B, is a separate piece, made in suitable lengths or sections and of the proper curvature for the ends or corners, and the rim or molding is adapted to fit upon the 40 top edges of the tub, and to being secured thereto by hydraulic cement or other suitable adhesive material. With this object in view, the top edges of the bath-tub may be rectangular in section, as seen in Fig. 1, or with a 45 grooved upper edge, as seen in Fig. 3, and the

rim or molding is to be hollow on the under surface and of any desired shape sectionally, so as to set over the edges of the bath-tub and be cemented thereto.

The exterior surfaces of the rim or molding 50 are to be ornamented by enamel in any suitable colors or figures, and the said surfaces may be smooth, ribbed, or figured.

By my improvement the rim or molding, being separate, can be fired or burned to any 55 desired extent, according to the quality of the clay and of the glaze, and the rim is not liable to injury in transportation, because it can be kept separate and cemented to the tub after the same is set in place and the pipes and fittings connected therewith.

It is to be understood that my invention applies to bath-tubs and separate rims or moldings of earthenware, china, terra-cotta, stoneware, glass, or any other ceramic material. 65 Dowels or pins may be used for securing the rim in place.

I claim as my invention—

1. As a new article of manufacture, an earthenware bath-tub with a separate earthenware 70 rim or molding cemented to the upper edges thereof, substantially as set forth.

2. An earthenware bath-tub having a plain upper edge, in combination with a separate rim of earthenware, made in sections and cemented upon the edges of the tub, substantially 75 as set forth.

3. The combination, with the ceramic bath-tub, of a ceramic rim in sections and recessed upon the under surfaces to fit over the edge of 80 the bath-tub and be cemented thereto, substantially as set forth.

Signed by me this 8th day of March, A. D. 1887.

WALTER CLIFF.
